RENEWABLE FUSE CASING

Ray Schoeppell, Huntington Park, Calif.

Application June 15, 1944, Serial No. 540,421

4 Claims. (Cl. 200—131)

1

My invention relates to cartridge-enclosed fuses, in which the fusible element or link may be replaced by the user when blown.

A principal object of my said invention is to provide for the fusible link and its terminal connections, a cartridge casing having a side opening extending the full length of the fusible element and its said connections, such openings facilitating not only inspection and insertion or replacement, when blown, of the fusible element, but also the tightening, loosening or other adjustment of its electrical contact holding means within the cartridge casing.

It is also an important object to provide such a cartridge casing with closure means for said side opening which, while closing with sufficient tightness to prevent lint and dust collecting around the fusible link and becoming ignited when the fuse is blown, is easily manually operated in opening and closing without the use of tools, and which will facilitate the operation of opening and closing, and will remain in closed position when so set until manually opened.

Still another important object is to provide contact clamping means for the fusible element within the cartridge casing, which are quickly and easily tightened or loosened by use of an ordinary hand wrench, and in which nuts and washers forming part of the clamping means cannot be easily removed from the casing and thus possibly misplaced or lost.

It is also a vital object to provide closure caps for the ends of the cartridge casing which, while permitting easy manipulation in opening and closing the side of the casing, effectually closes the respective ends of the casing, thus preventing ingress of dust or lint, and which closure cap also, by its rigid connection to the terminal blade extending through it and its telescopic extension within the casing, further facilitates tight closure of the casing while permitting its easy manual opening and closing operation.

Other important advantages, such as simplicity of construction, fewness of parts, ease of assembly, and consequent comparatively low cost of manufacture, will be apparent to all of skill in this art upon an examination of the following specification, illustrating my preferred embodiment in the light of the drawings forming part hereof, in which—

Fig. 1 is a side elevation of the complete assemblage of the device of my invention, showing side closure means of the casing in open position, and illustrating the fusible link within the casing and its contact clamping means;

2

Fig. 2 is a perspective view of the device shown in Fig. 1, with side opening of the casing in closed position;

Fig. 3 is a side elevation of the device, showing side opening of the casing closed;

Fig. 4 is a section on line 4—4 of Fig. 1, showing the clamping means in elevation;

Fig. 5 is a section on line 5—5 of Fig. 3, showing in elevation contact clamping means for the fusible element;

Fig. 6 is a section on line 6—6 of Fig. 3, showing spring means for restraining said closure means in closed position;

Fig. 7 is a section on line 7—7 of Fig. 1, showing certain parts in elevation;

Fig. 8 is a section on line 8—8 of Fig. 7, showing clamping means for the fusible element in elevation.

In the drawings, in which like numerals represent similar parts throughout the several views, 19 designates the cylindrical tubular outer shell of the cartridge casing, which shell is preferably of hard fibrous insulating material well known in the art. Within outer shell 19 is closely but rotatably telescoped inner cylindrical tubular shell 11 of the cartridge casing.

A cap 12 (of suitable metal well known in the art for the purpose) is provided with a peripheral flange 13, which is adapted to rotatably telescope over the outer adjoining end of outer shell 19. Cap 12 is also provided with a preferably integral sleeve 14 (Figs. 7 and 8) which telescopes snugly into adjoining end portions of inner cylindrical tubular shell 11 of the casing.

Cap 15, also of metal well known in the art for like purposes, is provided with a peripheral flange 16 which is adapted to rotatably telescope over the outer adjoining end of outer shell 19.

Cap 15 is provided with a preferably integral sleeve 17, which telescopes snugly into adjoining end portion of inner cylindrical tubular shell 11 of the casing.

Terminal blade 18 extends through and fits closely within the walls of a suitable diametrically placed slot 19 centered in the circular end of cap 12, extension 20 (Figs. 7 and 8) of said blade 18 within cap 12 being provided with a bore 21 (Fig. 8) through which passes a screw later to be described.

Terminal blade 22 extends through and fits closely within walls of a suitable diametrically placed slot 23 (Fig. 6) centered in the circular end of cap 15, extension 24 (Fig. 5) of said blade 22 within cap 15 being provided with a bore 25

(Fig. 8), through which passes a screw later to be referred to.

Through a suitable bore 26 (Fig. 8) adjacent an end of inner cylindrical shell 11 of the cartridge-casing extends a screw 27, which, after passing through a tapped bore through sleeve 14 of cap 12, passes through tapped bore 21 in terminal blade extension 20, and then passes through a slot (later to be described) in an adjoining end of fusible element 35, then through terminal washer 29, then through nut 28, and from thence through tapped bore 26a in the adjoining side of sleeve 14, said screw being riveted at its end in a countersunk hole (not numbered) in the inner shell 11.

Through a suitable bore 30 adjacent one end of inner cylindrical shell 11 of the cartridge-casing, extends screw 31, which, after passing through a tapped bore in sleeve 17 of cap 15, extends through nut 34 and then through terminal washer 33, then passing through tapped bore 25 in terminal extension 24, and from thence passing through a tapped bore through the opposite side of sleeve 17 of cap 15 and freely through a bore 30a in the adjoining side of inner shell 11, being there riveted in a countersunk hole (not numbered) in bore 30a. Outer shell 10 is provided with a bore (Fig. 8) adapted to register with the head of screw 31 for the insertion of a screw driver for assemblage purposes.

Opposite ends of fusible element 35 are provided with slots 36 and 37 (most clearly shown in Fig. 7), thus providing a hook at each end of the fusible link 35 for the reception of the shanks of screws 27 and 31, respectively, the respective slotted ends of fusible element 35 being clamped between the respective terminal washers 29 and 33 and each of the terminal blade extensions 20 and 24 of the terminal blades by tightening, respectively, nuts 28 and 34.

In order to restrain undesired relative movement between outer shell 10 and inner shell 11 when manipulated to closed position, I provide (Fig. 6) a bore 38 through outer shell 10 and inner shell 11, and extending into but not through sleeve 17 of cap 15, on the bottom of which last-mentioned bore is seated a helical spring 39. This bore 38 is of slightly smaller diameter through outer shell 10 than through inner shell 11 and into sleeve 17. Within the upper convolutions of helical spring 39 the shank of a semi-spherical headed pin 40 extends, said shank being shorter than depth of bore 38 and being slideable within said bore, its head, however, being of greater diameter than the bore 38 through outer shell 10. When shells 10 and 11 are manually rotated with respect to one another in opening the closure means, the edge of the bore 38 of the outer shell will ride over the rounded surface of the head of pin 40 and the diameter of said head being slightly less than the diameter of the bore into the members containing the helical spring, will be pushed within said bore, the outer shell compressing the pin against the expansion of helical spring 39, so as to permit relative rotating movement of the outer shell with respect to the inner shell.

It will be understood that numerous changes in size, design, shape and number of the various parts may be made; also that the cartridge cas-

ing may be composed of transparent instead of opaque material as shown in the drawings; and that other means than those specifically disclosed may be employed with like effect in connecting the fusible element between the terminals—all without departing from the spirit of my invention as defined in the appended claims.

What I claim and desire to secure by Letters Patent is:

1. In a cartridge-fuse-casing comprising a shell of insulating material, closure caps having peripheral flanges telescoped over the outer periphery of said shell, and having also inwardly extending sleeves telescoped within and engageable with the bore of said casing, and terminals extending into opposite ends of said shell through said sleeves, respectively.

2. In a cartridge-fuse-casing comprising an outer tubular shell and an inner tubular shell both of insulating material, said inner shell being telescoped within said outer shell, closure caps for said casing having peripheral flanges telescoped over the outer periphery of said outer shell, and which caps also have an inwardly extending sleeve telescoped within and engageable with said inner shell.

3. In a device of the character described, a pair of slotted tubular casings telescoped together, a terminal extending into each end of said casings, a pin projecting through each end of said inner casing and through the terminal thereat, said outer casing being rotatable over the ends of said pins to selectively register and misalign said slots, a fusible element suspended between said pins, and means to clamp said fusible element against each of said terminals.

4. In a device of the character described, a pair of slotted tubular casings telescoped together and formed of insulating material, a terminal extending into each end of said telescoped casings, a screw projecting through each of said terminals having its ends mounted in said inner casing, said inner casing having a slot therein the longitudinal axes of said screws lying in a common plane forming substantially right angles with a radial plane passing through said slot in said inner casing, a fusible strip having slotted ends adapted to engage said screws, respectively, and a nut threaded on each of said screws to clamp the slotted ends of the fusible strip to said terminals, respectively, said outer casing being rotatable on said inner casing over the ends of screws and having a slot therein registerable with the slot in said inner casing upon relative rotation between said casings.
